Cortlandt F. Ames, Inventor

By his Attorney, Chas. W. Mortimer

Patented Oct. 9, 1928.

UNITED STATES PATENT OFFICE.

CORTLANDT F. AMES, JR., OF MOUNT VERNON, NEW YORK, ASSIGNOR TO THE BARRETT COMPANY, A CORPORATION OF NEW JERSEY.

SHINGLE FASTENER.

Application filed January 31, 1924. Serial No. 689,702.

This invention relates to a device for holding the lower or exposed ends of flexible shingles in position.

It is frequently desirable to install manufactured shingles which are flexible and are sometimes liable to curl up in such a manner that the exposed portions terminate in pointed or relatively narrow portions. These narrow portions are liable to curl up when exposed to the weather or they are likely to be blown up by the wind.

In applying devices to prevent the extensions from flapping or curling, it is desirable to have them inexpensive and easy to install and they should also not mar the appearance of the roof.

By the present invention a device of this character is produced which serves to hold down the corners or extensions and is cheap to manufacture, easy to install and is inconspicuous. This device is especially applicable, for example, to shingles that are square or rhombus shaped and are installed in horizontal rows with their diagonal corners laid contiguous to each other or in horizontal lines.

The invention will be understood from the description in connection with the drawings, in which

Fig. 1 is a side view of the device or retaining member;

Fig. 2 is an edge view of the same;

Fig. 3 is a section along the line *a—a* of Fig. 2;

Figs. 4, 5 and 6 are sections of different shapes showing modifications of the cross-section of the material;

Fig. 7 is a side view of a modification;

Fig. 8 is a section along the line *b—b* of Fig. 7;

Fig. 9 shows another modification;

Figs. 10 and 11 are plan and edge views respectively of a shingle showing one of the devices attached thereto;

Figs. 12 and 13 show modifications of the shingles with the device attached;

Fig. 14 is a plan view showing a different modification of the device or retaining member;

Fig. 15 shows it applied to a shingle; and

Fig. 16 indicates how the shingles may be laid.

In the drawings reference character 1 indicates a U-shaped retaining member that may be made of any suitable material, such

as zinc, copper, wrought iron, etc. It may be rectangular in cross-section as shown in Fig. 3 or it may be of other shapes, some of which are illustrated in Figs. 4, 5 and 6, as having beveled edges, being oval in shape, or round, respectively. The lower ends of the member 1 may terminate in rounded or pointed portions 2 to make these ends somewhat sharp.

In the modification shown in Fig. 7 a piece of strap metal 3 is bent around to form the head 4 as shown with the ends forming prongs 5.

In the modification as shown in Fig. 9 a piece of wire 6 is bent around in a plane to form the head 7 with the ends of the wires forming the prongs 8. The retaining member 1 may be inserted through the lower corner of the shingle by causing the prongs to pierce the shingle after which the lower ends are bent outwardly as shown in Fig. 11, the intermediate portion 8 resting upon the surface of the shingle. In Fig. 13 the shingle itself is shown as being cut off along the line 9 parallel with the retaining member 1 and in Fig. 14 the corner is somewhat rounded as shown at 10.

The prongs piercing the shingle at 2 places spaced a short distance apart will prevent the retaining member 1 from being turned or twisted after it has been inserted. When the retaining member 1 is bent to the shape indicated in Fig. 7 it will pierce the shingle in a single place and will be prevented from turning by having its cross-section of the shape as indicated in Fig. 8.

Another modification of the retaining member 1 is shown in Fig. 14 in which a flat piece of metal 11 is slit along the lines 12 and the prongs 13 are bent downwardly along the dotted lines 14 and are bent outwardly after having passed through the shingle. The end of the extension 15 is bent under and backward so that its edge occupies the position shown by the dotted line 16. When this retaining device is applied to the shingle as indicated in Fig. 15, the prongs 13 extend beyond the edges of the shingle and the lower portion of the extension 15 passes around and under the end of the shingle which may be cut off to facilitate this.

A horizontal row of square-shaped shingles 17 may be installed as shown in Fig. 16, nails or similar fastening devices 18 being driven through near the horizontal corners thereof

into the roof deck. A similar row of shingles 19 is then installed above the first row 17 with the outwardly extending prongs of the retaining device projecting under the edges of the 5 shingles 17 and so on for successive courses. In this way there is no danger of having a nail hole extending from the outer surface of a shingle in any one place clear through to the roof deck with the attendant danger of leakage. 10 The portion of each overlying shingle that is pierced by one of the retaining members lies directly over a protecting portion of an underlying shingle that is not pierced through at this same point.

15 I claim:

1. A shingle retaining member comprising a flat strip of substantially uniform width and a wider but shorter portion contiguous to and integral with said strip intermediate 20 the ends thereof adapted to be formed into a shingle clamping hook.

2. A shingle retaining member comprising a flat strip of substantially uniform width and a wider but shorter portion contiguous to and 25 integral with said strip intermediate the ends thereof, said portion and strip being partially separated by slits at either end of said portion.

3. A shingle retaining member comprising 30 a flat strip of substantially uniform width and a trapezium shaped portion having its longest

side contiguous to and at least partially integral with said strip intermediate the ends thereof.

4. A shingle retaining member comprising 35 a flat strip of substantially uniform width and a trapezium shaped portion lying in the same plane as said strip and having its longest side contiguous to and at least partially integral with said strip intermediate the ends thereof. 40

5. In combination a shingle and a retaining member comprising a flat strip of substantially uniform width and a wider but shorter portion contiguous to and integral with said strip intermediate the ends 45 of said strip extending thru said shingle near one corner thereof and one side of said contiguous portion being bent around and underneath the edge of said shingle.

6. In combination a shingle and a retaining member comprising a flat strip of substantially uniform width and a trapezium shaped portion having its longest side contiguous to and at least partially integral with said strip intermediate the ends thereof, the ends of said 50 strip extending thru said shingle near one corner thereof and one side of said trapezium shaped portion being bent around and underneath the edge of said shingle. 55

In testimony whereof I affix my signature.

CORTLANDT F. AMES, JR.
